UNITED STATES PATENT OFFICE.

JAMES H. ALEXANDER, OF PHILADELPHIA, PENNSYLVANIA, ASSIGNOR TO
THOMAS DEVLIN & CO., OF SAME PLACE.

DESIGN FOR A CEILING-PLATE.

SPECIFICATION forming part of Design No. 19,518, dated December 24, 1889.

Application filed November 15, 1889. Serial No. 330,482. Term of patent 14 years.

To all whom it may concern:

Be it known that I, JAMES H. ALEXANDER, a citizen of the United States, residing in the city of Philadelphia, State of Pennsylvania, have invented a certain new and original Design for Ceiling-Plates, of which the following is a full, clear, and exact description, reference being had to the accompanying drawings, forming a part of this specification.

My design relates to ceiling-plates for steam and other pipes; and it consists, first, of a novel form or configuration, and, secondly, of the surface ornamentation of such a plate, as shown in the drawings and hereinafter described.

Referring to the drawings, Figure 1 is a front elevation of a ceiling-plate embodying my design. Fig. 2 is a side view thereof through the line x x of Fig. 1, and Fig. 3 is a

sectional view of the same.

The form or configuration of the plate is, as shown in Figs. 2 and 3, circular, curving upward to a central recess, with cylindrical rim F, the latter having on one side a projection E. In surface ornamentation the top for a short distance from the outer edge A is plain,

and from that plain surface to the central rim F there is a picked groundwork with a scalloped edge B. Proceeding outward from the inner rim F are three leaf-like projections C, and intermediate between each of the same are small ornamental figures D, both of the latter figures being raised work upon the picked groundwork B, the plain edge A being also raised with respect to the groundwork B in order to bring into more prominent relief the scalloped edge of the latter.

Having thus described my invention, what I claim is—

1. The design for the external configuration and surface ornamentation of a ceiling-plate, substantially as shown and described. 40

2. The design for the surface ornamentation of a ceiling-plate, substantially as shown and described. 45

In testimony whereof I have hereunto affixed my signature this 9th day of November, A. D. 1889.

JAMES H. ALEXANDER.
